DESIGN FOR A STAND

Winfield L. Holden and Theodore G. Linderme,
Detroit, Mich.

Application August 26, 1940, Serial No. 94,630

Term of patent 7 years

To all whom it may concern:

Be it known that we, Winfield L. Holden and Theodore G. Linderme, citizens of the United States of America, residing at Detroit, in the county of Wayne and State of Michigan, have invented a new, original, and ornamental Design for a Stand, of which the following is a specification, reference being had therein to the accompanying drawing, forming a part thereof.

The figure is a perspective view of a stand showing our new design.

The characteristic features of our design reside in the portions shown in solid lines.

We claim:

The ornamental design for a stand, substantially as shown and described.

WINFIELD L. HOLDEN.
THEODORE G. LINDERME.
